CLAIM

The ornamental design for an espresso coffee machine, as shown and described.

DESCRIPTION

The patent or application file contains at least one drawing executed in color. Copies of this patent or patent application publication with color drawing(s) will be provided by the Office upon request and payment of the necessary fee.

1. Espresso coffee machine

Fig. 1.1 (main design) is a front view of the coffee machine; fig. 1.2 is a side view thereof; fig. 1.3 is a perspective view (diagonal from above) thereof; fig. 1.4 is a top view thereof; the shadows on each reproduction are for illustrative purposes only and form no part of the claimed design; the relevant feature of the claimed design product is the shape of the coffee machine with its portion feed on top; the coffee balls in the portion feed are shown for illustration purposes only and form no part of the claimed design.

1 Claim, 4 Drawing Sheets
